UNITED STATES PATENT OFFICE.

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed November 16, 1923. Serial No. 675,090.

To all whom it may concern:

Be it known that I, HENRY C. HARRISON, a citizen of the United States of America, residing at Port Washington, in the county of 5 Nassau and State of New York, have invented certain new and useful Improvements in Electromagnetic Devices, of which the following is a full, clear, concise, and exact description.

10 This invention relates to electromagnetic devices, and particularly, to mountings for the vibratory members in such devices.

The object of the invention is to provide an armature mounting which is free from 15 relatively moving contact surfaces and torsional strains.

In accordance with the general features 20 of the invention, there is provided an armature having a plurality of rod like members parallel to its axis of rotation from which the armature is suspended by means of a plurality of resilient members attached to a support.

In one embodiment of the invention the 25 armature is provided with an axial member, from each end of which projects four short rods or studs parallel to the axis of rotation and symmetrically disposed with respect thereto and supported by means of thin 30 strips of metal passing around each stud, both ends of each strip being attached to a support whereby the forces restoring the armature are produced by the tensional stresses in these strips.

35 Referring to the drawing, Fig. 1 shows a phonograph reproducer embodying the invention.

Fig. 2 is a cross sectional view on the line 2-2 of Fig. 1.

40 Fig. 3 is a cross sectional view of the armature support.

Fig. 4 is a longitudinal view through the armature support.

45 For the purpose of illustrating the application of the invention, it is shown as applied to an electromagnetic reproducer such as disclosed in Patent No. 1,284,623 of November 12, 1918, to H. C. Egerton. An armature 37 of magnetic material is secured 50 intermediate its ends to an axial member 38, in each end of which are fitted and secured in any suitable manner such as soldering, four rods 5 extending parallel and symmetrical to its axis. The outer ends of the rods

5 may be secured by small disc 6 which may 55 be perforated to receive them.

Supports 41 for holding armature 37 in operative relation to the electromagnet 15 are provided with perforations 8 in each of which is secured a cylindrical bushing 9 having 60 four longitudinal grooves in its inner surface at substantially 90° apart. In these grooves are fitted four light flexible members 16 made of brass or copper foil or other suitable material bent at substantially 90°, 65 the ends of each flexible member being secured in the grooves spaced 90° apart. If preferred these four resilient members may be made by folding one sheet of material back and forth upon itself. Each of the 70 rods 5 project through the cylinder 9 and lie snugly in the angle of one of the resilient members 16, and may be soldered thereto if desired. The length of the web members 16 will depend upon the maximum displacement 75 of the armature, the greater the displacement the longer the members 16 should be. It will be seen from the construction herein described that all relatively moving contact surfaces which tend to produce rattle as in pivoted joints are dispensed with and the restoring force is provided mainly by the tension introduced in the web-like members.

What is claimed is:

1. A mounting for oscillatory members comprising an axial member parallel to the axis of oscillation, a plurality of rods attached parallel to said axial member, a support and resilient means securing said rods to said support.

2. In an electromagnetic device, an armature, a mounting for said armature comprising a plurality of rods extending transverse said armature and secured thereto, a support, 95 and means for suspending said rods from said support.

3. In an electromagnetic device, an armature, a mounting for said armature comprising an axial member transverse said armature and secured thereto, a plurality of spaced rods parallel to the axis of said axial member and projecting from the ends thereof, a support, and suspension means bent substantially at right angles connecting said 100 rods to said support.

4. In an electromagnetic device, a vibratory member, a mounting therefor, said

mounting comprising an axial member secured to said vibratory member, a plurality of rods parallel to said axial member and carried thereby, a support, and a plurality of resilient members, each end of said members being attached to said support and each member carrying one of said rods.

5. In an electromagnetic device, a vibratory member, means for supporting said vibratory member, said means comprising four parallel rods symmetrical with respect to the axis of said vibratory member, a support, and suspension members having their ends attached to said support, each of said 10 suspension members carrying one of said rods.

6. In an electromagnetic device, an oscillatory member, a hollow cylindrical support therefor having its axis in alignment with the axis of oscillation of said member, a plurality of angular resilient members within and secured to said support, said resilient members having angular portions converging toward the center of said support and a plurality of rods lying in the angular portions of said resilient members and attached to said oscillatory member.

15 In witness whereof, I hereunto subscribe my name this 12th day of November, A. D. 1923.

HENRY C. HARRISON.
